GARBAGE DISINFECTING DEVICE

Najam Modad and Louis Schneider, Carbondale,
Pa.

Application February 25, 1933. Serial No. 658,648

3 Claims. (Cl. 220—87)

The present invention relates generically to a novel and improved means for disinfecting garbage or the like. More specifically, the present invention has particular relation to a very practical and economical garbage can attachment of extremely simple construction, but of high efficiency.

A primary object of this invention is the provision of a disinfecting attachment of the character above mentioned, which attachment shall be capable of easy application to or association with garbage cans of standard construction, such as are available on the market at the present time.

A further object of the present invention is the provision of a device of the type outlined which shall be capable of easy salvage in the event the can to which it may be attached has, for one reason or another, to be discarded, and which device shall still be applicable to another can.

A still further object of the invention is to provide a disinfecting attachment which shall be adapted to be mounted, without involving the use of tools other than those commonly available, either to the top or cover of the can or to the bottom thereof, depending upon the character of the specific disinfecting medium involved, as will appear more clearly from the description hereinafter set forth.

A further object is to provide a device which shall be reliable in operation, which shall be easy and convenient to handle (as when filling or refilling), and which shall be of sufficiently rigid construction to be able to substantially permanently withstand the usage to which devices of this character are ordinarily subjected.

The foregoing and other objects and advantages of this invention will be apparent to those skilled in the art to which the invention pertains, from the detailed disclosure thereof hereininafter set forth. Applicants' novel relationship of parts is described in detail in the following description, which will be better understood by reference to the accompanying sheet of drawing, illustrating a preferred embodiment of the invention.

On the said sheet of drawing,

Fig. 1 is a view, partly in elevation and partly in section, of a conventional and standard form of garbage can, to the cover of which the present invention has been applied;

Fig. 2 is a view, partly in elevation and partly in section, of the top part of the can of Fig. 1, the can cover being raised and the attachment,

which constitutes the subject matter of the present invention, being open;

Fig. 3 is a front view of the attachment, per se, in closed condition;

Fig. 4 is a view corresponding to that of Fig. 3, but with the parts open; and

Fig. 5 is a view, partly in elevation and partly in section, of the lower part of a conventional garbage can, showing the present invention applied to the bottom thereof.

Similar reference characters designate corresponding parts throughout the several figures of drawing.

Reference numeral 10 designates a standard form of garbage can provided with a hinged top 70 or cover 11, which is adapted to be raised by the foot-operated lever system 12 to the position shown in Fig. 2. It is, of course, understood that the aforesaid system 12 may be omitted and the cover raised manually.

Attached to cover 11 of the can is the garbage disinfecting device which constitutes the present invention. This device or attachment, which is shown in closed position in Fig. 1 and in open position in Fig. 2, comprises a base or mounting plate 13, a disinfectant container 14, and a guard or outer casing 15.

The base or mounting plate 13 is preferably of the configuration illustrated in Fig. 4 of the drawing, and is provided adjacent each end thereof with perforations 16, whereby the attachment may be affixed to the cover 11 by means of bolts or the like 17 which pass through corresponding openings provided in the cover of the can.

Disinfectant container 14 is preferably of rectangular dished construction, and may conveniently consist of screenlike material. This container 14 is preferably hinged to base plate 13, substantially centrally thereof, by means of spring hinge 18.

Guard casing 15 is appreciably larger in size than container 14 (see Figs. 2 and 5), and is preferably substantially circular in cross section to correspond to the central circular portion of base plate 13 (see Fig. 4). Casing 15 is hinged to plate 13 adjacent one end of the latter, retaining means (hereinafter described) being provided adjacent the other end of the plate to securely maintain the casing 15 in closed position, in which position casing 15 encompasses container 14 in spaced relation thereto. One end of casing 15 is of course open, while the other end 19 is solid and imperforate. Peripheral wall 20 of casing 15 is provided with a plurality of perforations 21, sub-

stantially as illustrated. The casing 15 is made of relatively heavy gauge metal.

The retaining means, aforementioned, consists essentially of a strip of metal fabricated to form

5 a wedge-shaped locking lug 22 disposed on plate 13, see Figs. 3 and 4. A coating springy socket 23 is securely mounted on the juxtaposed portion of casing 15. Convenient means for opening casing 15 against the action of springy socket 10 23 is provided in the form of handle 24 affixed to casing 15 by means of bracket 25.

In the embodiment shown in Fig. 5, the attachment is exactly the same as that heretofore described, except that it is applied to the bottom 15 11^a of can 10^a in inverted position. In this case, handle 24 provides convenient means for lifting casing 15 to the position shown in Fig. 5.

Any desirable or suitable form of disinfectant material may be disposed in container 14. If 20 solid, it is placed directly within the container; if liquid, it may be applied to waste or the like which is then placed in the container. The chemical vapors evolved from the disinfectant pass into the interior of the garbage can through 25 openings 21 of the protective casing 15.

In the event that the chemical vapors of the disinfectant material used are heavier than air, the attachment provided by the present invention is mounted on the top of the can. If the disinfectant vapors are lighter than air, the device is mounted as illustrated in Fig. 5. In either case, protector casing 15 protects the disinfectant and container 14 from being crushed by or against the refuse and from becoming contaminated 35

therewith. Imperforate end 19 is of particular value in this connection, especially when the attachment is used on the bottom of the garbage can.

Although the preferred form of the invention 80 has been described in some detail, it is not intended thereby to limit the scope of the invention or otherwise than by the terms of the claims hereunto appended.

What is claimed is:

1. An attachment of the character described, particularly adapted for use with conventional garbage can constructions, said attachment comprising a base plate, means for attaching said plate to said can construction, a disinfectant container hingedly mounted on said base plate by means of a spring hinge, a substantially cylindrical protector casing hingedly mounted on said base plate and adapted to substantially encase said disinfectant container, and means to retain said casing in encasing position, said casing including a perforated peripheral wall and an imperforate end. 85 90 95

2. The construction defined in claim 1, said retaining means consisting of a locking lug mounted 100 on said base plate and a springy socket mounted on said casing, said lug and socket being adapted for interlocking engagement.

3. The construction defined in claim 1, said disinfectant container being of screen construction, 105 and said casing being of heavy gauge metal
